UNITED STATES PATENT OFFICE.

OSCAR A. SMITH, OF EAST CLEVELAND, AND RICHARD C. KINLEY, OF LAKEWOOD, OHIO,
ASSIGNORS TO THE NATIONAL ACME COMPANY, OF CLEVELAND, OHIO, A CORPORATION OF OHIO.

NUT-CASTELLATING MACHINE.

Application filed June 30, 1923. Serial No. 648,755.

This invention relates to nut castellating machines, an object of the invention being to provide improved mechanism for castellating nut blanks wherein all of the operations including the successive feeding of the blanks to the punching mechanism, the punching of the nut blanks and the extraction or ejection of the castellated blanks, will be performed automatically, thereby greatly decreasing the cost of labor, increasing the output, and improving the operation of the machine. The present improved machine therefore is so organized and operated as to result in a considerable reduction in the cost of production with an accompanying increase in efficiency and volume of output.

A further object of the present invention is to provide an improved machine for castellating nut blanks having mechanism automatically operated for feeding the nut blanks successively to the punching mechanism.

A further object of this invention is to provide a nut castellating machine having automatically operated mechanism for positively ejecting or discharging the nut blanks after they have been castellated by the punch mechanism.

A further object of this invention is to provide an improved nut castellating machine having means for feeding the nut blanks to the punch mechanism, means for positively ejecting or discharging the finished blanks and automatic means for operating the feeding and ejecting means.

Other objects of this invention will appear in the following description and appended claims, reference being had to the accompanying drawings forming a part of this specification, wherein like reference characters indicate corresponding parts in the several views and wherein Fig. 1 is a side view partly in section illustrating particularly the automatic mechanism for operating the blank feeding means and blank extracting means; Fig. 1^a is a detail view illustrating the operating cam shown in Fig. 1; Fig. 2 is a front view illustrating particularly the mechanism for controlling the feeding and extractor means, other parts of the machine being shown diagrammatically; Fig. 3 is a detail side view illustrating the change gear mechanism; Fig. 4 is a fragmentary sectional view illustrating the feeding or loading plunger mechanism; Fig. 5 is a detail plan

view showing the tension spring mechanism; Fig. 5^a is a detail view similar to Fig. 5 but partly in section; Fig. 6 is a sectional plan view illustrating the position of the punch holder and extractor or ejector; Fig. 7 is a left hand end view partly diagrammatical of the construction shown in Fig. 6; Fig. 8 is a vertical transverse section taken on line 8—8 of Fig. 6 and Fig. 9 is a detail sectional view showing the connection of the cam operated lever with the feed lever.

Before explaining in detail the present improvement and mode of operation thereof, we desire to have it understood that the invention is not limited to the details of construction and arrangement of parts which are illustrated in the accompanying drawings, since the invention is capable of other embodiments, and that the phraseology which we employ is for the purpose of description and not of limitation.

The present invention is an improvement over Patent No. 1,157,258 dated October 19, 1915, issued to Smith and Rindfleisch, and assigned to the National Acme Company, assignee of the present invention.

In the machine covered by said patent the blanks were fed successively from a magazine to the punch mechanism by means of a feed rod operated by a hand lever. Furthermore in this machine the finished blanks were extracted from the die mechanism by means of the gripping engagement of the end of the feed rod with the blank, so that upon withdrawing the feed rod the blank was withdrawn therewith and extracted upon coming in contact with the corner of a spring plunger. An operator was required to be in constant attendance on each castellating machine of this patent, since the feeding and extracting of the blanks was accomplished by hand. It has been found in practice that such a machine was not always fully efficient and effective in operation, due to the fact that the proper operation of the machine depended to a considerable extent upon the feeding and extracting of the nut blanks at the proper times, and where the exact timing of the feed and extraction of the blanks depended entirely upon the vigilance and judgment of the operator the required efficiency and speed in production was not fully obtained.

Furthermore, it has been found in practice that where the extraction of the finished blanks depended upon the frictional grip of

the end of the feed rod with the bore of the blank the most satisfactory and efficient results in the extraction of the blanks were not always obtained. These disadvantages 5 however are overcome by virtue of the present improvement, wherein the timing and the operation of the blank feeding and extracting means is automatically controlled by means of mechanism driven from the 10 main shaft, so that positive, efficient and accurate results are obtained with a maximum speed in operation.

Furthermore, as a result of the automatic 15 operation of the feeding means and the extracting or ejecting means, an operator is no longer constantly required at every machine, and it has been found in practice that the present improvement enables a single operator to attend to at least four machines 20 so that as a result the labor cost which is a most important item is cut down at least four times.

The present improved mechanism is especially designed for the purpose of punching 25 blanks, such as nut blanks having a cylindrical hole axially of the blank, and the machine embodies a punch press of any suitable type, a detailed description of which is not deemed necessary herein. Furthermore, only so much of the machine as is 30 necessary for an understanding of this invention is herein shown and described, many of the main parts of the machine, including the punch mechanism, being shown in my prior patent and in themselves forming no 35 part of this invention.

To the stand or base 2 of the machine is bolted at 3 a suitable bracket 4, and to the upper outer face of this bracket is bolted 40 a housing member 5. In suitable bearings in the upper portion of the housing 5 is mounted a shaft 6, and below this shaft at one side of the housing the latter is provided with a suitable bore in which is housed a 45 stud 7. Mounted upon the shaft 6 and the stud 7 are a series of change gears 8 which may be of the usual type well-known in all Acme machines.

Mounted upon the shaft 6 adjacent to the 50 change gears and resting against the outer face of the housing 5 and connected to the change gears in the usual manner is a chain driving sprocket 9. This sprocket is connected and driven by means of a chain 10 to a sprocket 11 secured to the outer end of the crank shaft 12 of the machine. The crank shaft 12 and sprocket 11 are shown diagrammatically in Fig. 3, the same being carried at the upper part of the machine 55 as shown in my prior patent. Thus, it will be seen that the shaft 6 is driven by means of the sprocket 9 from the main shaft through the medium of the change gears 8, and by means of these gears any required 60 speed ratio can be obtained at will. Loosely 65

mounted upon the driven shaft 6 is an actuating cam disk 13 which rests against the inner side of the bearing for the shaft 6 located at the side of the housing 5 opposite to the sprocket wheel 9. The cam disk 13 has an extended portion 14 and is provided with an angular cam groove 15. At one side of this cam disk and loosely mounted upon the shaft 6 is a hardened clutch collar or member 16, and cooperating with this clutch member is a clutch collar or member 17, the latter being slidably mounted upon the shaft 6 by means of a suitable key and key way (not shown). The clutch collars or members 16 and 17 are provided with suitable mating teeth and grooves, and the outer face of the member 17 is provided with a groove 18. A bracket 19 is bolted at 20 to the housing 5 (see Figs. 2 and 3), and to this bracket is pivoted by means of a bolt 20^a an operating lever 21, the lower end of the lever 21 being provided with suitable studs and rolls 22 which cooperate with the groove 18 in clutch member 17. By means of the lever 21 therefore, the clutch members 16 and 17 may be disconnected, thus disconnecting the cam 13 from the drive shaft 6, and by shifting the lever 21 to the position shown in Fig. 2, the clutch members 16 and 17 will be connected thereby driving the cam disk 13 from the shaft. Secured to the frame of the machine and extending therefrom are a pair of extensions or bars 23 which are spaced apart in parallel relation, and bolted to these bars is a magazine supporting bracket or housing 24. To the inner end of this bracket or housing is mounted in proper position a magazine 25. This magazine preferably comprises a vertical member 26 having a feed channel 26^a, and an inclined member 27 having a similar feed channel communicating therewith, members 26 and 27 of the magazine being bolted together as illustrated. The lower member 26 of the magazine at one side of the feed channel 26^a is provided with a vertical bore in which is housed a stripper plunger 28 and an actuating spring 29 bearing against the upper end of the plunger. The front part of the plunger 28 projects laterally through an opening 28^a, see Fig. 4, in the lower end of the magazine and is normally seated upon a notched edge 28^b of the housing 24, see Fig. 1, so as to extend partially into the channel 33. The lower end of the magazine forms with the magazine housing 24, a lengthwise extending channel 33 for receiving the nut blank and for permitting the reciprocation of the feed plunger which is operated to feed the blank from the magazine to the punch mechanism. At opposite sides of the housing 24 adjacent to the front thereof are bolted a pair of bracket members 30, the ends of these members being bent 120

outwardly at 31 in spaced relation to the feed channel and bored to receive plungers 32 which are in alignment with each other and which extend from opposite sides into 5 suitable bores in the lower end of the magazine and into the lengthwise extending channel 33. Springs 34 embrace the plungers 32 and maintain the same under tension.

The channel 33 extends rearwardly 10 through the housing 24 and forms a bore for receiving a feed plunger 35. The forward end of the plunger 35 is machined at 36 so as to fit into the bore of the nut blank, and the plunger is also slotted from the front 15 end a suitable distance rearwardly at 37 and tempered in order to provide resilient or tension jaws which will enter the bore of the blanks under tension. The rear end of the plunger 35 is provided with a bore 20 38 into which one end of a cushion plunger 39 extends, the opposite end of the plunger being provided with an enlarged portion 40 between which and the end of plunger 35 is mounted a tension spring 41. The cushion 25 plunger 39 is provided with a suitable lengthwise extending slot 42 through which a pin passes and which pin is fastened to the plunger 35. The purpose of this slot 42 is to permit a slight amount of lost motion. 30 The enlarged end 40 of cushion plunger 39 is slotted for the reception of one end of a connecting link 43, which is connected thereto by means of a pivot pin 44. The link 43 at one side thereof is provided with 35 a lengthwise extending V-shaped groove 45 terminating at opposite ends in stations 46 and 47 which are somewhat deeper than the groove 45. A lever 48 is pivoted at its lower end 49 to the housing 5, and the upper 40 end of this lever is crotched at 50 to receive and embrace the actuating link or member 43. Safety mechanism is provided for connecting together lever 48 and link 43, so that in case the feed plunger 35 is prevented 45 from operating through jamming of the feed passage 33 or through other cause, the safety mechanism will render the camming mechanism ineffective and prevent breakage of any parts. Secured to one side of the 50 lever 48 is a member 51 which is bored to receive a plunger 52 and a tension spring 53 acting against the plunger. The spring 53 has sufficient tension to force the plunger 52 into the station 46 and normally connect 55 together the lever 48 and link 43. In case the mechanism should become jammed or otherwise fail to operate the power applied to the lever 48 will overcome the tension of spring 53 and force the plunger out of the 60 station 46, thus permitting the lever 48 to shift relatively to the lever 43, the end of the plunger 52 traveling in the V-shaped groove 45.

Intermediate the ends of the lever 48 is 65 mounted a cam roller 54 which is adapted

to cooperate at the proper time with the cam groove 15 of the disc 13. This cam groove or slot comprises angular portions 15^a and 15^b, the groove 15^a acting to advance the feed plunger and retract the ejector 70 plunger, and the groove 15 acting to retract the feed plunger and advance the ejector. An ejector or extractor lever 55 is pivotally connected at its upper end 56 at a suitable point to the bearing block 57 for the punch mechanism, and the lower end of this lever is machined so as to enter a recess 58 machined in a connecting rod 59 which is mounted in a suitable groove in the under side of the bearing block 57. A connecting link 60 is pivotally connected to the end of the link 59, and the link 60 at its opposite end is slotted at 62 to receive a suitable pin 61 secured to the lever 48. The bearing block 57 is machined to provide a lengthwise 80 extending groove for receiving an ejector or extractor plunger 63. This ejector at one side is provided with a pin 64 which extends into a slot in the lever 55, and it will be seen that when the lever 55 is swung in 85 either direction the ejector 63 will be shifted lengthwise in the bearing block 57. The bearing block 57 is also recessed at 65 to receive a horizontally extending punch holder 66. This punch holder carries a 90 punch 67 having a lengthwise extending narrow rib projecting forwardly from the punch holder and forming a punch point 68. The punch holder 66 at its forward end is suitably machined or cut away at 95 69 and the ejector 63 at its forward end is provided with a laterally tapering offset portion 70 extending in juxtaposition to the machined portion 69, and the offset portion 70 of the ejector terminates in an ejector point 71. It will thus be seen that the ejector rests against and extends alongside of the punch holder, and although both the ejector point 71 and the punch point 68 are located approximately at the bore of the 100 nut blank 72, yet the construction is such that the operation of the punch will not interfere with the operation of the ejector, this being permitted by means of the relief portion 69 on the punch holder and the correspondingly offset portion 70 of the ejector. 105

Cooperating with the punch 67 is a die 73, which is preferably constructed in the manner illustrated in the aforesaid Patent No. 1,157,258, and the blanks 72 when fed into the die 73 are located and held in proper position by means of a holder plate 74 having spring tensioned jaws (not shown) for engagement with the flat faces of the nut blank. The construction of the holder plate 110 as well as the means for indexing and locking the die may be the same as in the above patent, and therefore a further detailed description thereof is not deemed necessary herein. The punch holder 66 is also con- 115

structed substantially in accordance with said patent and in like manner is supported horizontally and operated in a vertical path by means of a reciprocating ram 80 to punch the blank 72 from the inside out.

In the operation of the present improved machine, it will be understood that the mechanism is so timed by means of the change gears 8 and by the proper construction of the 10 cam disc 13 that upon the upward stroke of the ram 80, which operates against the punch in the manner described in the aforesaid patent, the plunger 35 through its actuating mechanism, carries a nut blank 72 into the 15 die 73, and after the ram has been operated to cause the punch 67 to punch six slots in the nut blank, the ejector plunger 63 is operated through the lever 55 to eject the finished nut blank. Thus, at one beat of the 20 ram the nut blank is fed into the die, and at another lost beat of the ram the nut is ejected from the die, so that with eight beats of the ram or press, one for loading and one for unloading, a complete nut is automatically 25 slotted.

The punch is returned to its original position in readiness for the next slotting operation by means of a spring plunger 85 which is supported below the punch holder 66. 30 The plunger 85 has a constant bearing upon the underside of the holder 66, and as the ram 80 descends this plunger is forced downward and a spring 86 is compressed. The position to which the punch is shifted is 35 controlled by adjusting nuts 87 on the lower end of the plunger 85.

By means of the cam 13, the lever 48 will be shifted forwardly, thus shifting the slotted end 36 of the plunger 35 into the bore 40 of a nut blank at the lower end of the magazine, and when the plunger 35 is shifted forwardly the nut blank engages the tapered ends 32^a of the tension plungers 32 which act to retard the nut blank sufficiently so as 45 to insure the end 36 of the plunger fully entering the bore of the blank. Also, when the blank is carried forwardly by the plunger 35, it engages the tapered corner 28^c of the plunger 28 which will be forced 50 upwardly out of the channel 33 against the action of spring 29, and at the same time assisting in retarding the blank to permit the slotted end 36 to fully enter the hole in the blank. When the nut blank has been fed 55 into the proper position in the die 73 the cam roller 54 passes out of the cam groove 15 and rides on the periphery of the cam disk 13, thus holding the lever 48 in forward position and the plunger 35 in its extreme 60 forward position. The spring 41 on the cushion plunger 39 at this time acts as a cushion when feeding the nut blank into the die and when holding the same during the slotting operation. If the nut blank does 65 not enter the die properly, then when the

plunger 35 withdraws the nut blank, the same will be extracted by engagement with the end of the plunger 28, thus acting as a stripper for removing the nut blank after it fails to enter the die properly.

After the nut blank has been properly slotted the cam roller 54 will pass into the groove 15 of the cam disk and will retract the lever 48, and at this time the ejector 63 will be shifted forwardly as the plunger 35 is shifted away from the die and will engage the nut blank and eject it from the die holder 74. The lever 48 normally is connected to the lever 43 by means of plunger 52 at station 46. If however, anything should happen to jam the magazine so that the nut blank would not pass into the die, the plunger 52 will be forced out of the station 46 permitting the lever 48 to shift relatively to the lever 43. Thus, this mechanism for connecting these levers forms a safety connection between the same to prevent breakage of the parts or jamming thereof. If the lever 48 shifts out of the station 46, as shown in Fig. 1, the machine is then stopped by the operator and the lever is pulled rearwardly to its proper working position.

A lost motion slot 62 on link 60 is provided so that the exact time for ejecting the blank will be secured. It has been found in practice that if the lever 48 is directly pivoted to link 60 the ejector may operate too soon, so that by means of this slot the exact time for extracting the nut blank can be determined.

Referring particularly to Figs. 6 and 7 it will be noted that the punch 67 has the working end 68 thereof extending approximately in the direction of the axis of the blank 72. The working end 71 of the ejector is located somewhat to one side of the axis of the blank so that when reciprocated it will engage the blank. By recessing the punch holder 66 at 69 and by offsetting the ejector at 70, it is possible to position the ejector at the same side of the blank as a punch which punches from the inside of the blank outwardly. The recessed portion 69 of the punch holder therefore permits reciprocatory movement of the ejector toward and from the blank, and the working end 71 of the ejector, although in juxtaposition to the working end 68 of the punch, does not interfere with the vertical reciprocation of the punch.

It is to be understood that by describing in detail herein any particular form, structure, or arrangement, it is not intended to limit the invention beyond the terms of the several claims or the requirements of the prior art.

Having thus explained the nature of this invention and described a way of constructing and using the same, although without attempting to set forth all of the forms in

which it may be made, or all of the modes of its use, we claim:

1. In a nut castellating machine, the combination of an indexible nut blank holder, a feed member for feeding a nut blank thereto, an ejecting member for ejecting the blanks from the holder, a reciprocating punch, mechanism for reciprocating the feed and ejecting members and including means for retracting the feed member prior to the advance of the ejecting member to eject a blank.

2. In a nut castellating machine, the combination of a nut blank holder, a feed member for feeding blanks thereto, an ejecting member, a punch supported and operated to punch the blank from the center opening outwardly, cam mechanism for shifting the feed and ejecting members and including means for shifting one prior to the other.

3. In a machine of the class described the combination of a punch, blank feeding mechanism, blank ejecting mechanism, a cam, means controlled by said cam for operating both of said mechanisms, said cam having a pair of angular cam faces for alternately advancing and retracting said mechanisms.

4. In a machine of the class described the combination of a blank feed plunger, an ejector, camming means, means controlled by said camming means for operating said feed plunger and ejector, said camming means having a pair of angular cam faces, one for retracting the feed plunger and for shifting the ejector to eject a blank, and the other for advancing the feed plunger and retracting the ejector.

5. In a machine of the class described, the combination of a punch, a blank feed plunger, an ejector, camming means, means controlled by said camming means for operating said feed plunger and ejector, said camming means having a pair of angular cam faces, one for retracting the feed plunger and for shifting the ejector to eject a blank, and the other for advancing the feed plunger and retracting the ejector, said camming means also having a cam face for maintaining said feed plunger in advanced position during the operation of the punch.

6. In a nut castellating machine, the combination of a nut blank holder, a punch supported and operated to castellate a blank, a feed member for feeding a blank to said holder, an ejecting member, and a common means for operating said feed and ejecting members and including a lost motion connection between said means and ejecting member.

7. In a nut castellating machine, the combination of a die, a horizontally located punch holder, a punch carried thereby, and a horizontally located blank ejector extending in juxtaposition to said punch holder,

said ejector having an inwardly offset portion extending toward the axis of said die.

8. In a machine of the class described the combination of a punch and an ejector having the working ends thereof located side by side, means for supporting said punch for operation thereof to punch a blank from the inside out, and means for supporting said ejector for movement transversely to the movement of said punch.

9. In a machine of the class described, the combination of a punch, blank feeding means, blank ejecting means, and a common means for simultaneously operating said feeding means and ejecting means in different directions, and including means for permitting one to commence movement prior to the other.

10. In a nut castellating machine, the combination of an indexible rotatable nut blank carrier, means for punching a blank carried by said carrier from the inside out, a magazine, means for feeding a nut blank from the magazine to the carrier and including a plunger, means for forcing the blank on to the plunger, means for stripping a blank from the plunger, ejecting means for ejecting the blank from the carrier, and power driven means for operating said blank feeding means, punching means and ejecting means in proper sequence.

11. In a nut castellating machine, the combination of an indexible rotatable nut blank carrier, means for punching a blank carried by said carrier from the inside out, a magazine, means for feeding a nut blank from the magazine to the carrier and including a plunger, safety mechanism for said blank feeding means, means for forcing the blank on to the plunger, means for stripping a blank from the plunger, ejecting means for ejecting the blank from the carrier, and power driven means for operating said blank feeding means, punching means and ejecting means in proper sequence.

12. In a nut castellating machine, the combination of an indexible rotatable nut blank carrier, means for punching a blank carried by said carrier from the inside out, a magazine, means for feeding a nut blank from the magazine to the carrier and including a plunger, safety mechanism for said blank feeding means, means for forcing the blank on to the plunger, means for stripping a blank from the plunger, ejecting means for ejecting the blank from the carrier and having a lost-motion connection, and power driven means for operating said blank feeding means, punching means and ejecting means in proper sequence.

Signed at Cleveland, Ohio, this 27 day of June 1923.

OSCAR A. SMITH.
RICHARD C. KINLEY.
